UNITED STATES PATENT OFFICE.

NELSON WILLIAM ALDOUS, OF TORONTO, ONTARIO, CANADA, ASSIGNOR OF ONE-HALF
TO NOAH SNYDER, OF TORONTO, CANADA.

RUG-WITHDRAWER.

1,087,096.

Specification of Letters Patent.

Patented Feb. 17, 1914.

Application filed October 30, 1912. Serial No. 728,700.

To all whom it may concern:

Be it known that I, NELSON WILLIAM ALDOUS, of the city of Toronto, in the county of York, in the Province of Ontario, Canada, have invented certain new and useful Improvements in Rug-Withdrawers, of which the following is the specification.

My invention relates to improvements in rug withdrawers and the object of the invention is to devise a simple means of quickly withdrawing any one rug from a pile of rugs without materially disturbing any of the other rugs in the pile and it consists essentially of a rod supported on suitable carriages at each side of the rug pile, means for attaching the end of one of the rugs thereto, means for revolving the rod, and means for adjusting the vertical height of the rod in relation to the pile of rugs as hereinafter more particularly explained by the following specification.

Figure 1, is a general perspective view of my device as applied to a pile of rugs. Fig. 2, is a vertical section through the rug pile showing my device in the position it assumes when starting to withdraw a rug from the pile. Fig. 3, is a similar view to Fig. 2 showing my device midway of its operation. Fig. 4, is a similar view to Figs. 2 and 3 showing my device in the position it assumes at the end of its operation. Fig. 5, is a perspective detail of one of the supporting carriages.

In the drawings like letters of reference indicate corresponding parts in each figure.

A is a pile of rugs.

B and B' are carriages comprising horizontal portions B² and B³ supported on rollers B⁴ and B⁵ and vertical double standards B⁶ and B⁷ connected together at the top by end pieces B⁸ and B⁹.

C and C' are threaded spindles journaled at their lower end in the horizontal portions B² and B³ and at their upper end in the end pieces B⁸ and B⁹. The upper ends of the spindles C and C' are preferably reduced and squared at C³ (see Fig. 5) to receive the turning cranks C⁴ and C⁵.

D is a block threaded on to each of the spindles C and C' so as to have vertical movement thereon. The outer end of each block is provided with a semi-circular recess D' in which are journaled bearing rollers D².

E is a rod resting in the recess D' on the rollers D² so as to revolve freely thereon.

E' are ratchet wheels secured at each end of the rod E.

E² are operating levers swung freely upon the rod E.

E³ are dogs pivoted on the pins E⁴ extending from the levers E². The dogs E³ are designed to engage with the ratchet wheels E' so as to turn the rod E by the backward and forward movement of the operating levers E².

F are a series of straps secured to the rod E.

F' are hooks secured to the straps F and designed to hook in to the end of the rug as shown particularly in Fig. 2.

Although I have shown hooks, it will of course, be understood, that various other devices such as clips may be used for connecting the rug to the straps.

Having described the principal parts involved in my invention I will briefly describe the operation of the same.

When it is desired to withdraw any one rug from the pile A my device is placed at the end of the pile as shown in Figs. 1 and 2. The vertical position of the rod E is then adjusted by turning the cranks C⁴ and C⁵ so that the rod is located slightly above the level of the rug selected in the pile. The hooks F' are then hooked in to the end of the rug at suitable distances apart and the rod revolved by means of the operating levers E². By this means the rug is gradually wound around the rod E and simultaneously the carriages B and B' are carried forward to each side of the pile as shown in Fig. 3 of the drawings. As the diameter of the roll of rug wound on the rod increases it may be necessary to adjust the vertical height of the rod E, so as to keep such roll free of the underlying rugs. This operation is continued until the roll passes free of the pile as shown in Fig. 4 of the drawings. The rug then may be readily unwound off the rod and placed on the top of the pile for the purpose of display.

It will be understood that the means hitherto employed for withdrawing a rug from a pile is very slow and laborious. In fact, so slow that few warehouse men will undertake to withdraw a rug merely for the purpose of display. Such means consists of turning each rug back half way of the pile until the rug selected is reached. This rug was then rolled up by hand midway of the pile.

- The overlying rugs would then have to be folded back and the other ends of the rugs would then have to be all turned up one at a time midway of the pile before the rug could 5 be withdrawn. This, of course, it will be readily seen is a long operation. By my device all that it is necessary to do is to attach the rug as above described and revolve the roller which will then pass directly through 10 the pile withdrawing the rug in a short space of time and with practically no labor. What I claim as my invention is.
1. A rug withdrawer comprising a revolving member set cross-wise at the end of 15 the pile, means for attaching the selected rug in the pile thereto, means for revolving the member to gradually roll the rug thereon, and vertically adjustable means for supporting the revolving member as it passes 20 through from one end to the other of the pile.
  2. A rug withdrawer comprising a revolving member, means for vertically adjusting said revolving member, means for connecting the rug selected thereto, anti-friction supporting carriages located at each 25 side of the pile, and designed to travel longitudinally of the pile automatically to carry the revolving member through the pile as the rug is wound thereon, as and for the 30 purpose specified.
  3. A rug withdrawer comprising a revolving member set crosswise at the end of the pile, a supporting means for revolving member, means for attaching the selected 35 rug in the pile thereto, means for revolving the member to gradually roll the rug thereon and means for adjusting the height of the revolving member on the supporting means, as and for the purpose specified.
  4. A rug withdrawer comprising a revolving member, straps secured to such member at suitable intervals, attaching means for connecting the end of the rug to the straps, means for revolving the revolv-

ing member, and supporting means for 45 carrying the revolving member through the pile as the rug is wound thereon, means for vertically adjusting said revolving member, as and for the purpose specified.

5. A rug withdrawer comprising a revolving member, means for attaching the end of the rug selected thereto, means for revolving the member, a carriage supporting each end of such revolving member, supporting rollers for the carriage, and means 50 located in the carriage for adjusting the vertical height of the revolving member, as and for the purpose specified.

6. A rug withdrawer comprising a revolving member, means for attaching the 60 end of the rug thereto, a ratchet and lever device for rotating the member, means for adjusting the height of said member, and a supporting carriage located at each end thereof designed to support the revolving 65 member as it passes longitudinally through the pile, as and for the purpose specified.

7. A rug withdrawer comprising a revolving member, means for attaching the end of the rug selected thereto, means for 70 revolving the member, supporting carriages located at each end of the member, vertical threaded spindles journaled in the carriage, blocks threaded on to the spindles, and designed to support the revolving member and 75 turning means for such spindle, as and for the purpose specified.

8. In a device of the type set forth, the combination with a carriage adapted for horizontal movement, of a vertically adjustable member supported thereby, means for securing a rug to said member, and means for rotating said member to wind the rug thereon.

NELSON WILLIAM ALDOUS.
